US00D699330S

(12) **United States Design Patent**
Ziemann et al.

(10) **Patent No.:** **US D699,330 S**
(45) **Date of Patent:** **** Feb. 11, 2014**

(54) **SINK**

(71) Applicant: **Blanco GmbH + Co KG**,
Oberderdingen (DE)

(72) Inventors: **Brigitte Ziemann**, Eppingen (DE);
Oliver Kuch, Oberderdingen (DE);
James Ryan Eder, Columbus, OH (US);
Oren Shai, Westerville, OH (US)

(73) Assignee: **BLANCO GmbH + Co KG**,
Oberderdingen (DE)

(**) Term: **14 Years**

(21) Appl. No.: **29/457,732**

(22) Filed: **Jun. 12, 2013**

(51) LOC (10) Cl. **23-02**

(52) U.S. Cl. **D23/293.1**
USPC **D23/293.1**

(58) **Field of Classification Search**
USPC D23/272-274, 284, 286, 292-293.1,
D23/303, 308; 4/619
